UNITED STATES PATENT OFFICE.

JOHN W. BEIGER, OF MISHAWAKA, INDIANA, ASSIGNOR TO BEIGER VENEER COMPANY, OF KELSO, WASHINGTON.

MACHINE FOR CUTTING VENEER.

Application filed November 21, 1923. Serial No. 676,062.

To all whom it may concern:

Be it known that I, JOHN W. BEIGER, a citizen of the United States, residing at Mishawaka, county of St. Joseph, State of Indiana, have invented certain new and useful Improvements in Machines for Cutting Veneer, of which the following is a specification.

This invention relates to improvements in machines for cutting veneer. It relates more particularly to the holder for the block or timber from which the veneer is cut, the same being in the nature of an attachment for rotary veneer cutting machine.

15 The objects of the invention are to provide an effective and simple attachment means for a rotary veneer machine whereby flat cross grain veneer may be readily cut without any undue waste of the timber.

20 Further objects, and objects relating to structural details will definitely appear from the detailed description to follow.

I accomplish the objects of my invention by the devices and means described in the 25 following specification. The invention is clearly defined and pointed out in the claims.

A structure which is a preferred embodiment of the invention is fully illustrated in the accompanying drawings forming a part 30 of this application, in which:

Fig. I is a side elevation view of the veneer cutting machine with my improved block holders in place.

Fig. II is a detail transverse sectional elevation view taken on line 2—2 of Fig. I showing an end view of the block holder and the relation of the veneer cutting knife.

Fig. III is an enlarged detail sectional elevation view taken on line 3—3 of Fig. I of 40 one of the holders.

In the drawings the sectional views are taken looking in the direction of the little arrows at the ends of the section lines and similar reference characters refer to similar 45 parts throughout the several views.

The parts of the drawings will be considered by their numbers. I have shown my invention associated with a regular construction of rotary veneer cutting machine in 50 which 1, 2 are end supports carrying the live

spindle and 3 is the opposite end support carrying the dead spindle. These supports are connected by the horizontal columns 4 which secure a rigid and strong construction for the heavy work required. 5 is the live 55 head carried on the live spindle 6 driven by the large pulley or gear 7. 8 is the dead head carried on the usual spindle, these parts all being of the usual construction of a veneer cutting lathe.

Between the spindles I carry a long rectangular beam or "stay log" 9 having preferably four faces. On each of the four faces I dispose one of my improved clamps which is disposed diagonally in relation 60 thereto. The same consists of a pair of clamp supports 10, 10' something like the jaws of a large vise held upon the face of the "stay log" by cap screws 11, 11 where the same is disposed well within the timber, 65 and by such screws and a cross bolt 12 where the support projects beyond the edge of the "stay log" or timber. The bolt extends diagonally down through the timber and is secured by a nut or head on the other end. 70

Between the stationary vise-like members 10, 10' I extend a heavy clamping jaw 14 provided with a projecting lip 15 for positively engaging the block or timber to be held. This jaw is supported by the angle 75 bar 13 secured thereto by suitable screws 13'. It is supported on its front by the larger angle bar 16 having the vertical limb 16' secured to the said clamp by rivets 17 and having a horizontal projecting limb 18. The 80 opposite vise members 10' are connected thereto by the usual vise structure 19 having a vise screw 26. It has a clamp bar 20 corresponding to the clamp 14 with an engaging lip 21. It is supported by an angle bar 22 85 similar to the angle bar 13 and by a heavy angle bar 23 having a vertical limb 23' secured thereto by rivets 24 and a horizontal limb 25 overlapping the horizontal portion 18 of the opposed stationary part, thus producing an exceedingly heavy clamp extending 90 the entire length of the "stay log" or beam.

A block or series of blocks of timber are supported within each of these clamps as 100

seen by the end view in Fig. II. The veneer cutting knife is of the usual construction having the heavy back 27 and a blade 28 disposed to cut a thin veneer from each 5 block or beam in succession as it is turned over toward it, the cutting operation being clearly indicated in Fig. II. Because the block or beam is placed on the diagonal the knife cuts the same with a clean gradual 10 cut without any waste or splintering of the timber. This facilitates the cutting of the veneer which may be of any size or in any way scarred so that it is unnecessary as in the usual rotary cut to slice the veneer after- 15 ward.

By this means a cross grain cut veneer or quarter cut sheet of veneer is very readily secured so that the grain of the lumber is presented and this is especially effective in 20 such work as battery divider or the like. It can also be used to cut veneer for ornamental purposes.

It will be observed from my description that I have in effect placed a large vise for 25 holding the lumber in oblique relation to the face of the central supporting beam or "stay log," the vise being so constructed that it has a very secure hold upon the timber holding it by one side so that the timber 30 can be substantially cut without waste, for the inch-thick board which is left is, of course, good lumber after the veneer has been cut from it.

I desire to claim the invention in the par- 35 ticular form shown and also broadly as pointed out in the appended claims.

Having thus described my invention, what I claim as new and desire to secure by Letters Patent, is:—

40 1. In a rotary veneer cutting machine, the combination of a square timber stay log supported by the spindles, pairs of vise-like clamps disposed in diagonal relation on the face thereof, pairs of oppositely facing, 45 obliquely disposed longitudinal jaws supported by the said clamps having inwardly projecting longitudinal lips, oppositely disposed pairs of angle bar supports for the said jaws each with a vertical member se- 50 cured to the said jaws and the horizontal members disposed towards the other in over- 55 lapping relation, and screw clamp means for the said jaws, the same being adapted to hold blocks or beams of timber in such relation as to be acted upon by the usual cutting knife of the said veneer cutting ma- 60 chine whereby veneer strips are cut from the beams or blocks successively in rotation.

2. In a rotary veneer cutting machine, 60 the combination of a square timber stay log supported by the spindles, vise-like clamps disposed in diagonal relation on the face thereof, pairs of oppositely facing obliquely disposed longitudinal jaws supported by the 65 said clamps having inwardly projecting lon-

gitudinal lips, oppositely disposed pairs of angle bar supports for the said jaws each with a vertical member secured to the said jaws and the horizontal members disposed towards the other in overlapping relation, 70 the same being adapted to hold blocks or beams of timber in such relation as to be acted upon by the usual cutting knife of the said veneer cutting machine whereby veneer strips are cut from the beams or 75 blocks successively in rotation.

3. In a veneer cutting machine, the combination with a stay log supported by the spindles thereof, of vise-like clamps disposed in diagonal relation thereon, pairs of 80 oppositely facing obliquely disposed horizontal jaws supported by said clamps having inwardly projecting longitudinal lips, oppositely disposed pairs of angle supports 85 for the said jaws, each with a vertical mem- ber secured to the said jaws and the hori- 90 zontal support members disposed each to- 95 wards the other in overlapping relation, as specified.

4. In a veneer cutting machine, the combination with a stay log supported by the spindles thereof, of vise-like clamps disposed in diagonal relation thereon, pairs of 95 oppositely facing obliquely disposed horizontal jaws supported by said clamps, oppo- 100 sitely disposed pairs of angle supports for the said jaws, each with a vertical member secured to the said jaws and the horizontal support members disposed each towards the other in overlapping relation, as specified. 100

5. In a veneer cutting machine, the combination with a stay log supported by the spindles thereof, of vise-like clamps disposed in diagonal relation thereon, pairs of 105 oppositely facing obliquely disposed hori- 110 zontal jaws supported by said clamps, as specified.

6. In a rotary veneer cutting machine, the combination with a "stay-log" supported by the spindles thereof, vise-like clamp mem- 110 bers with obliquely disposed longitudinal jaws arranged in parallel relation on the said "stay-log," the same being adapted to hold blocks or beams of timber in such re- 115 lation as to be acted upon by the usual cutting knife of said veneer cutting ma- 120 chine whereby veneer strips are cut from the beams or blocks successively in rota- 125 tion.

7. In a veneer cutting machine, the combination with a "stay-log" supported by the spindles thereof, vise-like clamps dis- 120 posed in diagonal relation thereon, pairs of oppositely facing obliquely disposed longi- 125 tudinal jaws supported by said clamps hav- 130 ing inwardly projecting longitudinal lips, oppositely disposed pairs of angle bar sup- ports for the said jaws, each with a vertical member secured to the said jaws and the horizontal members disposed each towards

the other in overlapping relation, and screw clamp means for the said jaws, as specified.

8. In a rotary veneer cutting machine the combination with a "stay-log" supported by the spindles thereof, of pairs of oppositely facing obliquely disposed longitudinal jaws

suitably supported thereon with means for clamping the same into engagement with blocks or beams of wood, as specified.

In witness whereof, I have hereunto set my hand and seal.

JOHN W. BEIGER. [L. s.]
